UNITED STATES PATENT OFFICE.

JOHN DAVID MAIN SMITH, OF EDGEASTON, ENGLAND, ASSIGNOR TO W. & J. GECRCE LIMITED, OF BIRMINGHAM, ENGLAND.

CRUCIBLE.

Application filed June 8, 1926, Serial No. 114,424, and in Great Britain June 5, 1925.

This invention has reference to improvements in or relating to crucibles employed in chemical analysis.

With crucibles for this purpose now generally in use in which crucibles the lid rests on and overhangs the rim of the crucible body it is frequently found that the results are unreliable or the determination rendered abortive by reason of the loss of contents of the crucible due to such causes as the decrepitation of solid matter, the creeping of liquids between the crucible and the undersurface of the lid, by the fracture of the lid, or again by the sudden lifting or dislodgment of the lid due to the violent liberation of gases or vapours whereby loss of contents may ensue by spouting or otherwise. Loss may also occur in these determinations where it is required to add further reagents to the contents of the crucible since in order to effect these additions it is necessary to remove the crucible lid thereby exposing the determination to risk of error by reason of loss of contents from one cause or another.

The present invention has for its object the provision of an improved crucible for use in chemical analysis whereby the aforementioned sources of error are eliminated to a great extent and the determinations effected with greater accuracy than heretofore and with a minimum of attention.

The invention consists of an improved crucible for use in chemical analysis wherein the crucible body is provided with a lid adapted to be located within the body so that the peripheral edge of the said lid is disposed below the rim of the crucible body, said lid being provided with a flange within which are formed a plurality of serrations or apertures.

The invention will now be described with particular reference to the accompanying sheet of drawings, wherein:

Figure 1 is a part sectional front elevation of a crucible constructed in accordance with the invention.

Figure 2 is a section on the plane indicated by the line 2—2 Figure 1 looking in the direction of the arrow in the said figure.

Figure 3 is a front elevation of the crucible lid, and

Figure 4 is a plan of Figure 3.

The crucible body 5 which may be made of fused silica or other suitable material is

of the ordinary shape and is of a size larger than that of the crucible of normal pattern that would ordinarily be employed for the operation contemplated. The crucible is closed by means of a lid 6 which fits within the crucible body so that the upper surface of the lid 6 is below the plane of the mouth of the crucible the lid being provided on the upper surface thereof with the usual annular member 6^a which is adapted to be engaged by tongs or other implements when it is desired to remove the lid from the crucible.

The lid 6 is formed with a substantially vertically depending flange 6^b within which is formed a plurality of serrations or apertures 6^c the depth of the said flange being such that when the crucible lid is disposed within the body the lower edge of the flange 6^b contacts with the inner periphery of the crucible body and supports the lid the portion of the flange above the said edge being separated from the walls of the crucible by an annular space which is in communication with the interior of the crucible body by means of the serrations or apertures 6^c in the flange 6^b as is clearly indicated in Figure 1.

It will be appreciated that with a crucible constructed in accordance with this invention the disadvantages resulting from the employment of the ordinary crucible provided with a lid adapted to rest and overhang the crucible body, are largely eliminated. For example, according to the present invention loss of contents due to decrepitation or spouting is prevented since the sole means of egress of the contents from the crucible body is by way of the serrations in the flange of the crucible lid and by reason of the juxtaposition of the outer periphery of said rim to the inner periphery of the crucible body such of the contents of the crucible as may escape through the serrations in the flange are merely discharged on to the walls of the crucible body and are not lost. Or again, in the case of the creeping of a liquid the liquid merely passes, at the places of contact of crucible and lid, from crucible to lid, owing to the temperature gradient between heated crucible and cooler lid.

Further, if it be desired to add any reagents such addition may be made without removing the lid whereby loss of the contents due to any possible violent chemical action is

avoided. Moreover, in the event of breakage of the lid from any cause no loss will result since the residual contents will still remain within the crucible body.

- 5 By reason of the advantages accruing from a crucible constructed in accordance with the invention due to the elimination of the sources of error referred to the duration of the determinations can be considerably 10 reduced since the degree of care and attention is less than that required in determinations with crucibles of known construction.

I wish it to be understood that I do not limit the invention to crucibles of fused 15 silica as it is equally applicable to crucibles made from other materials, for example, porcelain, fire-clay, nickel, or other metal, and further, if it be desired to employ crucibles of the standard size the reduction in 20 the effective capacity due to the location of the lid within the body of the crucible may

be compensated for by forming the lid of a dome shape.

Claims:

1. A crucible for use in chemical analysis 25 comprising a crucible body, a lid adapted to be located within the body so that the peripheral edge of the said lid is disposed below the rim of the crucible body, and a plurality of serrations or apertures in the said 30 lid.

2. A crucible for use in chemical analysis comprising a crucible body, a lid adapted to be located within the body so that the peripheral edge of the said lid is disposed below the rim of the crucible body, a flange on said lid and a plurality of serrations or 35 apertures formed in the said flange.

In testimony whereof, I have signed my name to this specification.

JOHN DAVID MAIN SMITH.
